LAZARUS SHAPIRO, OF NEW YORK, N. Y.

ELECTROMAGNETIC TRANSLATING DEVICE.

Application filed April 11, 1927. Serial No. 182,555.

My present invention relates to electromagnetic devices for translating voice currents into sound waves or vice versa, an example of such devices to which my invention is applicable being loud speakers of the cone type. More particularly, my invention relates to improving the construction of such devices in a manner which will obviate difficulties heretofore had in the commercial manufacture thereof, it being a main object of my invention to provide improved means for holding the armature and improved methods of assembling and adjusting the same.

In devices of the type to be described, it is common to mount the armature on a spring, usually of the torsional type. Heretofore, the manner of mounting such a spring has given rise to considerable difficulty in adjusting the position of the armature between the pole pieces, one reason for this difficulty being that in making the adjustment operation the spring would become slightly flexed and therefore would nullify the attempts at adjustment by again assuming its unstrained position upon completion of the supposed adjustment operation. By virtue of my improved construction, however, I am enabled to adjust the armature both rotatively and by movement of translation in its plane of vibration so as to accurately position same with respect to the pole pieces and without straining the supporting spring.

A further object of the invention is to provide improved means for attaching the drive rod to the armature whereby the leverage obtained may be suitably reduced or otherwise varied. My invention further contemplates an improved support for the drive rod whereby such support offers substantially no impedance to the movement of the rod.

A further object is to provide an improved coil mounting which shall prevent the coil from rotating and from getting out of place.

Other objects and advantages of the invention will be apparent as the description proceeds, such additional features being specifically pointed out in the claims.

In the drawings, Figure 1 shows in assembled form an illustrative embodiment of my invention, parts being broken away and in section;

Figure 2 is a top view of the device shown in Figure 1, the coil housing being broken away;

Figure 3 is a side view seen from the right of Figure 1, the cone having been removed;

Figure 4 is a sectional view taken on line 4—4 of Figure 1;

Figure 5 is a view taken on section 5—5 of Figure 4;

Figure 6 is a sectional view taken on line 6—6 of Figure 4;

Figure 7 is a perspective view of the armature and supporting spring, and

Figure 8 is a plan view of an armature coil.

Referring now to the drawings in detail, 10 denotes the permanent magnet usual in devices of this type to which are attached the pole pieces 13 and 14, bolts 11, 11 and nuts 12, 12 serving for this purpose. Conveniently, the shanks of bolts 11 adjacent the heads thereof are made of square cross section, accommodated by square openings in pole pieces 13 and 14 as shown, in order that the nut 12 may be screwed tight without turning the shanks.

In the preferred form of the device the pole pieces 13 and 14 are of approximately horseshoe shape and juxtaposed so as to provide a space in which is mounted the armature 16 (and the armature coils), leaving at either end of the armature two air gaps of small dimensions, one on each side of the armature. The region of the pole pieces opposite the armature ends form poles 17, 18, 19 and 20 respectively. It will thus be seen that in the present form of construction there are four air gaps, one between each pole and the armature. The adjustment of these gaps to exact quality and predetermined length is one of the main features of the present invention, this adjustment being one of the most important factors in determining the performance of a device of the character referred to in the present application.

Armature 16 is mounted preferably on a flat torsional spring 22, being suitably secured to said spring in preferably the following manner: Spring 22 is made in two halves 22^a, 22^b, which partially surround armature 16 and are soldered thereto. It will be obvious that various other means forming no part of the present invention may be em-

ployed to secure the armature 16 to the spring 22, as by having the spring in one piece and passing the armature 16 through an aperture therein.

6 The preferred composite armature support forms a rectangular Z as shown. It will be noted that in the preferred embodiment under description, spring 22 has flat portions or arms 22^c, 22^d extending at right angles 10 to its own plane and in planes parallel to that of the vibration of armature 16, the significance and importance of which will be dealt with hereinafter. Arms 22^c and 22^d are respectively secured to the device by 15 means of blocks 24 and 25, one of which, 24, is best seen in Figures 2 and 6. Blocks 24, 25, which are of brass or other non-magnetic material, engage pole pieces 13 and 14, block 24, for example, being secured to and 20 bridging poles 17 and 18 and block 25 engaging poles 19 and 20. Screws 26, 27, 28 and 29 pass through poles 17-20 respectively, screws 26 and 27 being threaded into block 24, and screws 28 and 29 into block 25, reference to Figure 1 showing this construction. 25 As shown in Figure 5 pole pieces 13 and 14 are provided with four slightly elongated slots 30 for accommodating screws 26-29 respectively, the slot construction being for 30 adjustment purposes as will be gone into more fully below.

Enough of the device has been described for an understanding of the mode of assembling the armature and the adjustment of 35 the air gaps to which my invention is largely directed. In assembling the device, the armature coils 32 and 33 (to be described in greater detail hereinafter) are first placed around armature 16. Shims 35, 35 of horse- 40 shoe shape as shown and of a thickness equal to that of the desired air gap are then placed in position as shown in Figure 5, the screws 26-29 inclusive, inserted and preferably screwed in partly so as to hold the pole 45 pieces 13 and 14 slidably in place and the foregoing assembly of devices placed within a fixture having clamping members diagrammatically indicated by the arrows to the right and left of Figure 5. By such means pressure is applied longitudinally of the pole 50 pieces, it being noted that due to the slots 30 in the pole pieces accommodating screws 26 to 29 inclusive, the pole pieces 13 and 14 will be pressed tightly against the shims 55 separating the armature 16 and poles 17-20, thereby establishing positively the desired positions of the armature and the pole pieces relative to each other. After pressure is applied in this way the screws 26- 60 29 are tightened and thus secure the armature and the pole pieces permanently in their proper relation to one another. It will be noted that the arms 22^c and 22^d of the spring 22, are also provided at their extremities 65 with transversely extending elongated slots,

22^c and 22^d respectively, these slots registering respectively with central, threaded bores in each of blocks 24 and 25, each receiving a screw 37 in contact with a washer 37^a (Figure 2). It will now be noted that 70 the slotted construction of the arms 22^c, 22^d of the spring will permit said spring freely to assume its correct position as established by the position of the armature and will afford any necessary adjustment movement of the spring angularly about the axis of rotation of the armature together with any movement of translation of the armature (and spring) necessary for said armature completely to accommodate itself between 80 the air gaps occupied by the shims without setting up torsional or transverse stresses or deformations of the spring. Accordingly, while the parts are held in their correct, predetermined position by the clamping device (not shown) screws 26-29 inclusive and 37, 37, are screwed tight. The clamps are then removed and the shims are pulled out, whereupon the parts remain permanently secured in their proper relative 90 positions. If desired, the above procedure may be varied somewhat by first permanently attaching spring 22 to the respective blocks 24, 25 and the entire adjustment obtained by means of screws 26-29 inclusive 95 binding the blocks to the pole pieces.

From the foregoing, it will be seen that when a spring of the torsional type is used, an adjustment movement in a single direction is sufficient to adjust the armature both 100 rotatively about its axis of vibration and if necessary in a movement of translation in the same plane. These two movements are sufficient to obtain complete adjustment. Otherwise expressed, the above described 105 method of adjustment involves merely the placing of the armature in its correct position with respect to pole pieces, as by shims (or other e. g. visual means) while the support for such armature is free to assume 110 such position as it will, and then merely tightening the screws securing such support to the device without in any way disturbing the assumed position of the armature support or in any way altering the tension of 115 the armature spring.

It now remains to describe certain further elements exemplifying other features of the invention. Armature 16—see Figure 7—has an offset 40 having a number of 120 notches 41 for the purpose of securing in proper position with reference to the center of movement of the armature, the drive rod 43, and after the assembling operation above described such drive rod 43 is soldered in 125 that one of the notches 41 which will give the correct leverage demanded by the particular type of vibrating cone or diaphragm (45) used. Drive rod 43 having been attached, the assembled pole pieces, armature 130

and armature coils are now attached to the magnet 10 by means of bolts 11 already described.

A further feature of my invention consists in novel means of supporting the drive rod 43, consisting in a member 47 (Figure 3) of special shape which is held in place by one of the bolts 11 and prevented from rotation by means of an inwardly extending tab 48 (Figure 5) engaging a hole or recess 49 in pole piece 14. Support 47 has a downwardly (from the position shown in the drawing) extending portion or arm having apertures 50 adapted to have drive rod 43 pass through them, these apertures registering substantially with notches 41 on offset 40 of armature 16. Element 47, which is of light, flexible material will be thus seen to afford a complete support for drive rod 43 while in no way interfering with the movement of the armature or drive rod. Drive rod 43 is joined to cone 45 by means of the usual set screw construction 52.

One of the important results obtained by the above described arrangement is the fact that the three notches 41 and the three holes 50 enable the manufacturer to control the effective mass of the cone as transmitted to the armature, and thereby to control the fundamental frequency determined by the mass and the spring. This control is commercially important, inasmuch as there is a variance of opinion regarding the desirable range of frequencies to be covered by a good loud speaker. By securing the drive rod in the outermost notch, for example, the transferred mass of the cone is increased and the fundamental frequency is lowered together with the whole range of frequencies reproduced; and vice versa, by choosing the innermost notch, the range of frequencies is shifted toward a higher pitch.

The armature coils 32, 33 also present a feature of the invention in that they are provided with an exterior casing 55 somewhat larger than the opening between the sections 13 and 14 of the pole plate and have notches 56, 57 which engage the inner sides of the pole pieces, this being best seen in Figure 4. Pole pieces 13 and 14 are also constructed so as to maintain the armature coils separated by the proper amount, such construction involving the use of lugs 58, 59 extending from the inner sides of the pole pieces—see Figure 5. A housing is preferably provided for the coil and armature attaching means, such housing being preferably constructed of two halves 60 and 61 which are placed on opposite sides of the pole pieces and clamped against the pole pieces by means of bolts 62, 63. Within the casing on one of the halves thereof I have the usual terminal connections 64, 65 properly insulated and connected to the ends of the composite coil.

I wish it understood that various details of the above described embodiment may be considerably varied without departing from the spirit of my invention.

What I claim is:

1. In an electro-magnetic translating device having an air gap, an armature co-operating with said gap, a mounting for said armature, a portion of said device and said mounting having co-operating surfaces extending parallel to the plane of vibration of the armature, and means for securing said mounting to said portion of the device permitting relative movement of said co-operating surfaces to permit of adjustment of the armature in said plane of vibration. 75

2. In an electro-magnetic sound translating device having an air space, an armature extending within said space, a mounting for said armature comprising a spring having attaching portions which include clamping surfaces parallel to the plane of vibration of the armature, and means for securing said portions to the device permitting adjustment movement of the armature both of translation and of rotation in its plane of vibration. 90

3. In an electro-magnetic sound translating device having pole pieces providing an air space, an armature extending within said space, a mounting for said armature comprising a spring having an attaching portion extending parallel to the plane of vibration of the armature, and common means for securing to each other the pole pieces forming the air space and said attaching portion. 95

4. In an electro-magnetic translating device having two pairs of oppositely disposed poles providing a pair of air spaces, an armature having its ends extending within said spaces, a mounting for said armature comprising a spring intermediate the ends thereof, said spring having oppositely extending attaching arms which are parallel to the plane of vibration of the armature, and common means for attaching one of said arms and a pair of said poles in adjusted relation. 110

5. In an electro-magnetic sound translating device, a mounting for an armature comprising a spring member of rectangular Z shape, said spring member sustaining the armature intermediate and substantially parallel to the arms of the Z. 115

6. In an electro-magnetic sound translating device, a mounting for an armature comprising a spring member of rectangular Z shape, said spring member sustaining the armature intermediate and substantially parallel to the arms of the Z, the ends of said mounting having transversely extending slots for attaching same to the device. 125

7. In combination, an armature for an electro-magnetic translating device, said

4
armature having an offset portion at right angles to its plane of vibration and adapted to have a vibrator drive rod attached thereto in proper position intermediate an end 5 of said armature and its transverse axis, a support for said drive rod comprising an arm spaced from said armature and means for attaching said support to said device.

8. In combination, an armature for an 10 electro-magnetic translating device, said armature having an offset portion at right angles to its plane of vibration and adapted

to have a vibrator drive rod attached thereto in proper position intermediate an end 15 of said armature and its transverse axis, and a support for said drive rod comprising a depending arm spaced from said armature and having apertures through one of which the drive rod is adapted to pass, depending upon the adjusted position of said drive rod. 20

In testimony whereof I have affixed my signature to this specification.

LAZARUS SHAPIRO.
